UNITED STATES PATENT OFFICE.

HARLEY BROOMHALL, OF SHELBY, OHIO, ASSIGNOR TO THE SHELBY METAL PRODUCTS COMPANY, OF SHELBY, OHIO, A CORPORATION OF OHIO.

KNOB MOUNTING.

Application filed April 16, 1926. Serial No. 102,456.

This invention relates to an improvement in knob mounting, and means of making the same, whereby the knob mounting and knob are interlocked for rotative movement through the provision of parts associated with and forming part of the knob mounting, and constructed wholly of sheet metal.

The construction involves the provision in sheet metal of the plate proper with which through beading step there is interlocked or associated an escutcheon ring, while the knob formed of sheet metal is provided with and interlocked to a washer, designed to be rotatively associated with the escutcheon ring through a simple beading movement of such ring. Thus the construction largely involves the provision of a ring, which through a simple mechanical operation is fixed to the knob mounting proper and serves to rotatively support the knob member without the use of visible or additional fastenings.

The invention is illustrated in the accompanying drawings, in which:

Fig. 1 is a view in elevation of the escutcheon plate proper.

Fig. 2 is an elevation of the escutcheon ring.

Fig. 3 is a vertical section of the same.

Fig. 4 is an elevation of the plate with the ring applied.

Fig. 5 is a section on line 5-5 of Fig. 4.

Fig. 6 is a rear elevation of the knob.

Fig. 7 is a vertical section of the same.

Fig. 8 is a vertical section through the interconnecting washer.

Fig. 9 is a front elevation of the same.

Fig. 10 is a vertical sectional view through the knob, showing the washer associated therewith.

Fig. 11 is a vertical sectional view through the complete assembly.

The escutcheon plate proper, indicated at 1, is made up of sheet metal appropriately stamped to provide an ornamental edge flange 2, screw holes 3 and a central opening 4. An escutcheon ring, as shown in Figs. 2 and 3, is constructed of sheet metal and formed to provide an inner ring extension 5 of a size to fit snugly within the hole 4 in the escutcheon plate, and an outer ring extension 6 of greater diameter than the inner ring extension, these ring extensions being connected by an intermediate section 7 at right angles to the axis of the ring.

The knob to be associated with the escutcheon plate is constructed of sheet metal, stamped to provide a body 8 of appropriate form, slotted at 9 for die drawing purposes, the otherwise closed inner end being formed with an opening 10. The body has a flaring edge 11 with which is associated a rounded or ornamental cap piece 12, the edge of which is beaded around the body edge 11 at 13, thus completing the knob.

An interconnecting washer completes the parts necessary to the assembly, this washer being shown more particularly in Figs. 8 and 9, and comprising a circular plate 14 of a diameter corresponding to the interior diameter of the ring extension 6 of the escutcheon ring. The interconnecting washer is formed with a non-circular aperture 15, the material cut from the washer in stamping the aperture being turned out from the washer plane in the form of holding prongs 16.

In assembling the parts, the escutcheon ring is associated with the escutcheon plate by passing the ring extension 5 through the opening 4, and beading the inner edge of such ring extension to embrace the edge of the opening, as indicated at 17 in Fig. 5. The interconnecting washer is then associated with the knob proper by passing the prong 6 through the opening 10 and pressing said prongs on the inner side of the knob body bottom to thereby interlock the washer and knob as indicated at 18 in Fig. 10. Of course, the association of the interconnecting washer and knob is carried out prior to the application of the cap 12 to the knob body. As the diameter of the interconnecting washer is somewhat greater than the adjacent end of the knob body, the washer presents an annular projecting edge 19 at the inner end of the knob, and the washer is then seated within the ring extension 6 of the escutcheon ring and the projecting portion of this ring extension is beaded over the flange projection of the washer as shown at 20 in Fig. 11. The non-circular opening 15 in the interconnecting washer is thus arranged in alignment with and centrally of the opening 4 in the escutcheon plate, and receives the usual connecting bar between the knobs indicated at 21.

It is to be particularly noted that all parts are constructed of sheet metal, that the knob is rotatively interlocked with the escutcheon

plate through means involving a mere beading or spreading of a sheet metal part, with the entire avoidance of visible or auxiliary fastening means. The method permits a convenient and rapid assemblage of the parts into the desired unit through a simple spreading and clamping action of sheet metal parts, while at the same time permitting a convenient separation of such parts 10 for the renewal of any defective part.

What is claimed as new, is:

An escutcheon plate and knob assembly, comprising a plate formed with an opening, a ring member having an enlarged circular 15 flange to overlie the plate and a reduced cir-

cular flange to fit within said opening, the reduced circular flange being of such dimension as to permit it to be beaded over the inner side of the escutcheon plate, a knob, a washer formed with a non-circular opening 20 and having integral prongs for connecting the washer to the knob, the diameter of said washer corresponding to the enlarged circular flange of the ring to permit the washer to be inserted within said flange, with the flange of a length to be beaded over to hold the washer against other than rotative movement with respect to the rim. 25

In testimony whereof I affix my signature.

HARLEY BROOMHALL.
